UNITED STATES PATENT OFFICE

143,658

DESIGN FOR A SEPARATOR FOR DISPLAY- ING MERCHANDISE

Floyd A. Hedrick, Vancouver, Wash., assignor of one-half to Fred G. Snyder, Vanport, Oreg.

Application July 18, 1945, Serial No. 120,779

Term of patent 3½ years

(Cl. D80—9)

To all whom it may concern:

Be it known that I, Floyd A. Hedrick, a citizen of the United States, residing at Vancouver, in the county of Clark and State of Washington, have invented a new original, and ornamental
Design for Separator for Displaying Merchandise, of which the following is a specification, reference being had to the accompanying drawing, forming a part thereof.

In the drawing:

Figure 1 is a perspective view of a separator for displaying merchandise, showing my new design.

I claim:

The ornamental design for a separator for displaying merchandise, as shown.

FLOYD A. HEDRICK.
